UNITED STATES PATENT OFFICE.

ALONZO J. SIMMONS, OF INDIANAPOLIS, INDIANA.

FURNACE FOR CONSUMING SMOKE.

SPECIFICATION forming part of Letters Patent No. 257,092, dated April 25, 1882.

Application filed January 25, 1882. (No model.)

To all whom it may concern:

Be it known that I, ALONZO J. SIMMONS, of Indianapolis, in the county of Marion and State of Indiana, have invented certain new and useful Improvements in Attachments to Furnaces for Arresting and Consuming Gases and other Products of Combustion; and I do hereby declare that the following is a full, clear, and exact description of the invention, which will enable others skilled in the art to which it appertains to make and use the same, reference being had to the accompanying drawings, which form a part of this specification.

My invention relates to means for arresting and consuming gases and other products of combustion. The object of it is to catch the unconsumed particles of fuel, together with the heavier gases as they come under the petticoat-pipe or strike the bottom of the smoke-arch and reconvey them back upon the burning fuel, after having been commingled with steam, or steam and air.

To this end my invention consists in means for conveying the gases and small particles of carbon from the smoke-arch and beneath the petticoat-pipe to a drum or chamber located in front of the fire-box, or at any other convenient place from which the fire-box may be reached, whence the unconsumed particles and heavy gases are conveyed to or forced upon the fire.

It further consists in a drum located in front of the fire-box, or at any other suitable place from which the fire-box may be reached, and having pipes leading therethrough to the smoke-arch and beneath the petticoat-pipe, and from the top of the drum to a series of vacuum-injectors connected to a pipe leading from the steam-dome.

It further consists in details of construction that will be hereinafter more fully set forth in the specification and claims, and pointed out in the accompanying drawings, in which—

Figure 1 is a vertical section of my device, in which the products of combustion and gases are directed into the furnace from the receiving-drum by a tube leading from the drum to the furnace; Fig. 2, a section of same, showing the means for drawing in the exterior air, the conducting-tube being dispensed with; Fig. 3, a plan view taken on the line *x* *x*, Fig.

1; and Fig. 4, a detail view of one of the injectors.

Referring more particularly to the drawings, A indicates the boiler; D, the steam-dome; B, the flues.

Opening into the smoke-arch, and beneath the petticoat-pipe, is a pipe, F, which extends downward to a drum, G, which for convenience is located in front of the fire-box, although it is obvious that it may be placed in any other suitable place from which the fire-box may be reached, without departing from the spirit of my invention. Below this pipe F, and within the drum, is a vacuum-injector, G, having the orifice *o* in its lower part, opening through the side of the drum to the outer air. This injector is fully described and claimed in another application now pending, and it will be sufficient for the purpose here to state that the steam from the dome is admitted to one part of the injector by the annular space *f*; while the gases and products of combustion are admitted or drawn through the opening *u* in the lower part, and the steam and said products of combustion are commingled beyond the apex of the lower part. The action of the steam admitted in this way creates a high vacuum in the drum, and this draws down rapidly and with great force the gases and particles of unconsumed carbon, &c., as they approach the smoke-arch and petticoat-pipe on their way from the flues to the smoke-arch P. As they are drawn downward into the drum the tendency of the heavier gases and unconsumed particles is to fall toward the bottom of the drum, and here they are met by the action of steam drawn from one branch of pipe leading from the steam-dome D, and they are then and there commingled with the steam and outer air, and thus commingled are forced onto the burning fuel to be consumed. The lighter gases rising in the drum are carried off by pipe F' and brought through cross-joints or connections *g'* to a series of injectors, *g*, where they are commingled with steam and forced upon the burning fuel. This is shown more fully in Fig. 2. The action just described goes on continuously.

It is well known that monoxide gases are heavier than any other gaseous product of combustion. Now, as the carbon monoxides pass through the flues they fall to the under side,

and as they are forced out of the flues the tendency is to fall to the under side of the smoke-arch with the heavier unconsumed particles, where they are drawn into pipe F and conveyed to drum G and commingled with steam and air, thus taking hydrogen and oxygen, the latter assisting in combustion, the former forming carbides of hydrogen. Consequently these and other gases and the particles of unconsumed fuel are by conversion again consumed. There are many advantages thus obtained. The great saving of fuel is the most important factor. By this means we are enabled to obtain a rapid and perfect combustion of the fuel, for if a lump of coal be burned slowly the minimum mechanical force is obtained therefrom, but if burned quickly the maximum force is obtained.

The cross-joints g' have screw-plugs p , by means of which the connections can be cleaned when necessary.

The shield N in the top of the drum prevents any particles of carbon from entering pipe F' with the lighter gases. By my device I cause not only a rapid combustion of the fuel, but save those particles and gases before lost through the smoke-stack.

Having thus described my invention, what I claim as new, and desire to secure by Letters Patent, is—

1. The method of consuming particles of carbon and gases arising from combustion of fuel in furnaces, which consists in arresting said

unconsumed products as they come under the petticoat-pipe, then conducting them to a drum 35 or receptacle provided with a vacuum injector or injectors in its lower end and a pipe at its upper end, which conducts the lighter gases to a series of injectors, where they are commingled with steam and forced into the furnace, substantially as set forth.

2. In a device for consuming the products of combustion in furnaces, a drum connected with the smoke-arch beneath the petticoat-pipe, said drum having a lower pipe leading 45 to the furnace, an upper pipe connected with a series of vacuum-injectors whereby steam is admitted, and a shield for preventing particles of carbon from entering said upper pipe, substantially as set forth. 50

3. In combination with a furnace, a drum, G, provided with a vacuum-injector, g, pipe F, entering the fire-box, pipe F', leading to the smoke-arch beneath the petticoat-pipe, pipe E, leading from the steam-dome, and pipe F', provided with a series of injectors, g, through which the products of combustion are forced upon the burning fuel, substantially as and for the purpose set forth. 55

In testimony that I claim the foregoing as my own I have hereto affixed my signature in presence of two witnesses.

ALONZO J. SIMMONS.
